METAL EDGE BOX STAYING MACHINE

William D. Stanger, deceased, late of Seaside Park, N. J., by Esther M. Stanger, executrix, Seaside Park, N. J., assignor to Louis Wolf, Elkins Park, Elias Wolf, Dresher, Howard A. Wolf, Jenkintown, and Walter L. Wolf, Rydal, Pa., co-partners, trading as National Metal Edge Box Company, Philadelphia, Pa.

Application November 24, 1941, Serial No. 420,192

3 Claims. (Cl. 1—12)

This invention relates to that type of box or other article, usually constructed of cardboard, in which meeting edges of adjacent walls or sections of the article are permanently secured together and (or) reinforced, by means of a metal strip overlapping such edges. Said metal strip, as most usually constructed, has near each of its opposite longitudinal edges a row of holes with prongs extending from the peripheries of the holes and penetrating the cardboard and, upset so as to be embedded in the material of the cardboard or clinched on the reverse side, and an intermediate row of holes extending along the longitudinal center of the strip and which extends over the adjacent edges of adjacent sections of the article. The strip is applied to the article by positioning it in a die or hammer, which is moved toward an anvil (to which said sections have been applied) to bend the strip along its longitudinal edge against the adjacent faces of the sections and force the prongs into or through the material and upset and clinch them as above described. The adjacent faces of the anvil are smooth flat surfaces corresponding to the shape of the article to be stayed and the die recess has smooth flat surfaces corresponding to the smooth flat surfaces of the anvil.

Other metal strips or stays are provided with only a single row of fasteners. In other metal strips the fasteners of a row are staggered. Other metal strips are not provided with a row of perforations along that longitudinal section of the strip which extends over the meeting edges of the walls or sections of the article to be stayed.

An article the meeting edges of which are joined and reinforced as above described is open to the objection that, in the bending of the strip along its longitudinal center, that is, directly through the central longitudinal row of perforations (if the strip contains such perforations), the metal surrounding and immediately adjacent such perforations is so distorted that the reinforced corner is decidedly rough—sufficiently so as to scratch varnished surfaces and prevent free telescoping, such, for example, as the sliding of a box lid on and off a box body. The object of the invention is to completely eliminate this roughness.

The object of this invention is accomplished by the modified construction of die and anvil hereinafter described and illustrated in the accompanying drawings, wherein—

Fig. 1 is a perspective view of the die which cooperates with the anvil to bend the metal strip

over two angularly disposed sections of an article and force prongs of the strip into fastening engagement with the material. Fig. 2 is an end view of the die and anvil with the adjacent sections of the article shown in section. Fig. 3 is an end view, and Fig. 4 is a perspective view, of the two sections of the article after their union. Fig. 5 is a side elevation of the box staying machine.

In Fig. 5 is shown a staying machine of the type to which this invention may be applied. It comprises a frame *k* on which is mounted driving means *m* having a connection (not shown) with a lever *n* connected by a link *o* with a die-carrier *p* carrying a die *c*. The die carrier and die are movable up and down on the frame *k* by actuating the treadle *r* connected to the driving mechanism. The anvil *a* is fixed to the frame. The metal strip *e* is fed to the die *c* and is held in longitudinally extending grooves therein, preparatory to the staying operation, as shown in Fig. 2. For a further description of machines of this type, reference is made to the Stokes Patent No. 793,549, issued June 27, 1905; the Jackson and Horton Patent No. 1,192,201, issued July 25, 1916; the Walz and Morris Patent No. 1,346,573, issued July 13, 1920; the Stanger Patent No. 1,918,922, issued July 18, 1933; and the Wismer Patent No. 2,070,767, issued February 16, 1937.

To the anvil *a* is applied the two pieces of material *f*, *f'*, which are to be secured together. The edges of the pieces meet at the ridge or corner of the anvil. The corner of the anvil is provided with a longitudinally extending recess *d*. The bottom of the die recess is provided with a longitudinally extending rib *b*. When the die *c* is moved downward against the material on the anvil, the projections on the strip *e*, as heretofore described, penetrate the material and secure together the meeting edges of the box sections *f* and *f'*. At the same time the rib *b* presses the meeting edges of the sections *f*, *f'* into the groove *d*, draws together the stayed edges, and so bends in and buries any rough edges of the perforations that may be formed in the operation of bending the metal strip as to produce, along the line of perforations, a perfectly smooth surface.

The rib or blade *b* in the die recess may be made integral with the die, but it is preferred to make it as a separate member and confine it in a slot in the die. The rib *b* need not be shaped as shown, its shape, thickness and size being variable to adapt it to different sizes and forms of metal stays. It is not necessary in all cases to

provide at the apex of the anvil a recess *d* that has a shape precisely complementary to the rib *b*. In some cases the anvil may be merely flattened at the apex and in other cases the sharp corner of the anvil may be retained.

The invention is applicable not only to the staying of box corners, but also to the staying of the meeting edges of any article, although it finds its most useful application to staying the meeting edges of sections of articles which meet one another at an angle.

Even where the metal strip is unprovided with a row of perforations extending over the meeting edges of the angularly disposed sections of the article to be stayed, it is advantageous to use this invention; and it should therefore be understood that, except in those claims which are otherwise expressly limited, the invention is not limited in its application to operating upon any particular type of metal stay.

What is claimed and desired to be protected by Letters Patent is:

1. Means for staying the meeting edges of the angularly disposed walls of an article by the application thereto of a metal strip and bending the same around said meeting edges, said means comprising an anvil having two faces extending at an angle to each other, a die having a recess whose faces extend at the same angle to each other and which are complementary to the anvil faces, and a rib extending longitudinally along the bottom of the recess of the die, the anvil be-

ing recessed along the corner or apex thereof for reception of the rib.

2. Means for staying the meeting edges of the walls of an article by the application thereto of a metal strip provided with fastening prongs and with a row of perforations, said means comprising an anvil having two faces extending at an angle to each other, a die having a recess whose faces extend at the same angle to each other and which are complementary to the anvil faces, and a rib extending longitudinally along the bottom of the recess of the die, the anvil being recessed along the corner or apex thereof for reception of the rib.

3. Means for staying the meeting edges of articles by the application thereto of a metal strip provided with prongs and with a row of perforations, said means comprising an anvil adapted to hold adjacent sections of the article with their edges substantially meeting, a die having a shape complementary to that of the anvil and adapted, in its movement toward the anvil, to force the prongs of the strip into fastening engagement with the sections of the article, and a rib, on the striking face of the die, adapted to align with said row of perforations, the anvil having a longitudinally extending groove adapted to align with said row of perforations and with the rib on the die.

ESTHER M. STANGER,
*Executrix of the Estate of William D. Stanger,
Deceased.*
